BOOK HOLDER AND DESK TOP

William James Bargen, Waukegan, Ill.

Application September 7, 1951, Serial No. 245,516

2 Claims. (Cl. 45—61)

1

This invention relates to a combined desk or table top, a book holder or controller, and a base adapted to be engaged by the book holder.

An object of this invention is to provide a tilting and elevating top for desks or tables in combination with a book holder or controller which is adapted to hold a book or other material on a predetermined angle to the vertical irrespective of the angular position of the top.

Another object of this invention is to provide a desk or table top and a book holder or controller, together with means for firmly holding the book holder at any point about the flat upper surface of the top regardless of the angular position of the top.

A further object of this invention is to provide a paper or sheet holder which will frictionally hold the paper at any point on the surface of the top and will also provide an antislip means for the book holder or controller when the top is tilted.

A further object of this invention is to provide a desk or table top which constitutes a sight saving device wherein the book holder and paper holder work with the top in the angular adjustment of the latter so that a student will sit properly while adjusting these devices to his needs as to the arms, eyes and shoulders.

With the above and other objects in view, my invention consists in the arrangement, combination and details of construction disclosed in the drawings and specification, and then more particularly pointed out in the appended claims.

In the drawings,

Figure 1 is a plan view partly broken away, of a desk top constructed according to an embodiment of this invention, including a book holder and paper holder.

Figure 2 is a detail end elevation of the desk top and holder.

Figure 3 is a front elevation of the book holder.

Figure 4 is a fragmentary sectional view taken on the line 4—4 of Figure 1.

Figure 5 is a fragmentary plan view showing the book holder in a second position on the surface of the top.

Figure 6 is a fragmentary sectional view taken on the line 6—6 of Figure 5.

Figure 7 is a fragmentary plan view showing the paper holder engaged with the trough at the front of the top.

Figure 8 is a fragmentary sectional view taken on the line 8—8 of Figure 7.

Figure 9 is a plan view, partly broken away, of

2

the paper holder and friction base for the book holder.

Figure 10 is a bottom plan view of the top.

Figure 11 is a diagrammatic view showing the adjusted position of the top relative to the book holder.

Figure 12 is a diagrammatic view showing the top in an extreme tilted position and showing in dotted lines the elevated position of the top.

10 Referring to the drawings, the numeral 15 designates generally a top structure which includes a plate 16 having opposite end depending flanges 17 and 18, and a rear flange 19. The top 15 is formed with a rearwardly projecting arm 20 at one end thereof, and is also formed with a second rearwardly projecting arm 21 which is slightly shorter in length than the arm 20.

The end flange 17 is continued about the arm 20 as indicated at 22, and the flange 22 merges with the flange 19. The flange 18 extends along the outer edge of the arm 20 and continues about the margin of the arm 20, as indicated at 23. The flange 23 merges with the adjacent end of the rear flange 19.

25 A transversely extending bracing rib 24 projects from the top plate 16 rearwardly from the forward edge thereof, and longitudinal flanges 25 and 26 extend from the flange 24 rearwardly. The flange 26 connects with a transverse flange 27 which extends from the adjacent end of the rear flange 19.

A forked flange 28 extends from the flange 25 and connects at the open forward end thereof with the forward flange 24. A similar forked flange 29 extends from the forward end of flange 26. One side of forked flange 29 extends forwardly, as indicated at 30, and is connected with a downwardly offset trough 31 disposed at the forward end of the top 15. A flange 32 extends 30 from one side of the forked flange 29 and also connects with the trough 31.

The trough 31 also includes a front wall 34 which projects upwardly above the surface of the plate 16. The forked flanges 28 and 29 provide a means for securing a lifting or elevating means 35 to the lower side of the plate 16.

45 A book holder generally designated as 36 is adapted to be disposed on the upper side of the top 15 and includes a plate 37 having a right angular lower wall 38, and an upwardly inclined book retaining flange 39. The book holder 36 includes an adjustable supporting arm 40 which is pivoted on a transversely disposed bar 41 carried by a slide 42. The slide 42 engages a vertically disposed guide 43 disposed on the rear side

55

of the plate 37, and plate 37 is provided with a plurality of spaced keeper openings 44.

The supporting arm 40 is provided with a locking lug 45 which is engageable in a selected one of the keeper openings 44. The arm 40 is yieldably held in either collapsed or extended position by means of a spring 46. The forward or lower end of the arm 40 is provided with a hook 47 engageable in the trough 31 and with the undercut or inclined rear wall 33 so that the holder will be held against downward sliding movement when the top 15 is inclined downwardly and rearwardly from its forward end.

The book holder 36 also includes a pair of feet members 48 formed with notches 49. In order to provide a means whereby the book holder 36 may be firmly and immovably mounted on the upper surface of the top 15 when the hook 47 is disengaged from the trough 31, I have provided an anti-slip member generally designated as 50.

The anti-slip member 50 includes an elongated plate 51 having ribbed rubber plates 52 and 53 fixed to the opposite faces thereof. An upwardly projecting flange 54 extends from one longitudinal edge of the plate 51 and the flange 54, as shown in Figure 6, is adapted to engage in one of the notches 49 of each foot member 48.

The anti-slip member 50, as shown in Figure 1, may also be used to hold a paper sheet S on the upper side of the top 15. The ribbed and resilient construction of the cushion members 52 and 53 provides the anti-slip means whereby the anti-slip member 50 may be disposed in a position shown in Figure 6, at any point about the surface of the top 15. The anti-slip member 50 may be inverted, as shown in Figure 8, wherein the flange 54 projects downwardly into the trough 31. The weight of the anti-slip member 50, together with the ribbed construction of the rubber members 52 and 53 will provide a means whereby the sheet S will be firmly held on the surface of the top 15.

Referring now to Figures 11 and 12, the top 15 is shown in full lines in Figure 11, in substantially horizontal position, and in Figure 12 is shown in full lines in the extreme tilted position. The dotted lines in Figure 11 show the several adjusted positions which may be assumed by the top 15 and it will be noted particularly in Figure 11, that as the forward edge of the top 15 is raised upwardly, the rear edge thereof will be proportionately moved forwardly. In the event that during the time the top is inclined relative to the supporting book box 55 it is desired to remove articles from the book box, the top 15 may be raised upwardly at its rear end to substantially a horizontal position, thereby permitting free access to the interior of the book box 55. The

forward wall 34 of the trough 31 provides a means whereby in the event the rear of the top 15 is raised above the horizontal, any books, papers or the like on the upper surface of the top 15 will be held by the wall 34 against sliding off from the forward end of the top 15.

The elevating means 35 comprises a pair of levers pivoted as at 56 to the forward wall of the box 55, and the elevating means 35 is pivotally secured as at 57 to the lower side of the top 15. This double and spaced pivotal mounting of the top 15 provides a means whereby the top may be tilted upwardly at its forward edge, and the top may also be elevated to a parallel position with respect to the box 15 by rocking the top on the pivot 57.

I do not mean to confine myself to the exact details of construction herein disclosed, but claim all variations falling within the purview of the appended claims.

What I claim is:

1. A paper holder for holding paper on a flat inclined surface comprising an elongated plate, a serrated cushion member fixed to one face of said plate, and a flange projecting from one longitudinal edge of said plate beyond the face of said cushion member for engagement with the upper edge of said inclined surface.

2. In combination, an inclined desk top, and an anti-slip paper holder engageable on the upper surface of said top, said holder including an elongated plate, a cushion member fixed on one face of said plate, a right angular flange carried by one longitudinal edge of said plate and projecting from said one face of said plate, said cushion member holding a flat sheet between the desk top against movement and said flange engageable with the top edge of the desk top to thereby hold the holder adjacent the top edge of the desk top.

WILLIAM JAMES BARGEN.
